TROUSERS HANGER

Sylvester J. Rowe, Chicago, Ill.

Application January 7, 1959, Serial No. 785,407

2 Claims. (Cl. 223—96)

This invention is an improvement of the trousers hanger disclosed in my United States Patent No. 2,806,641 issued to me on September 17, 1957 and my invention relates specifically to trousers hangers which are adapted to clamp the trousers legs between two hingedly related members which are easily manipulated to operative trousers clamping position and to inoperative non clamping position; and the nature and objects of the invention will be readily recognized and understood by those skilled in the arts to which it relates in the light of the following explanation and detailed description of the accompanying drawings illustrating what I at present believe to be preferred embodiments or mechanical expressions of my invention from among various other forms, arrangements, combinations and constructions, of which the invention is capable within the spirit and scope thereof.

While I am aware of prior art hangers for trousers which involve a pair of hingedly related clamping members I know of no hanger having simplified mechanism whereby the clamping members are hingedly related in such a manner that the locking of the member together into operative clamping position is accomplished merely by pressing the members together, while the release of the members into inoperative non-clamping position is effected merely by applying pressure at a particular location on one of the members.

This highly advantageous and desirable action is obtained by my novel hinge mounting of the two coactive members, a hinge mounting arrangement which not only provides for pivotal relative swinging movement of the members but also provides for relative axial movement of the members to position catch means on the members to move into and out of locking position.

In achieving the objects of this invention it has been one of my prime purposes to provide a simplified form of hinge which is inexpensive to produce and simple and easy to assemble into an operating unit. The importance of economy of production and assembly will be recognized when it is appreciated that the ultimate cost of hangers of this type must be kept relatively low in order to have consumer appeal.

In making simplicity and ease of operation an inherent attribute of my invention I have not sacrificed strength and long lasting characteristics for there are few operating parts and these are so mounted and arranged that they will be maintained in good working condition over long periods of time.

With the foregoing general objects, features and results in view, as well as certain others which will be apparent from the following explanation, the invention consists in certain novel features in design, construction, mounting and combination of elements, as will be more fully and particularly referred to and specified hereinafter.

Referring to the accompanying drawings:

Fig. 1 is a view in side elevation of the trousers hanger with the members thereof in operative trousers clamping position.

Fig. 2 is a top plan view of the trousers hanger.

2

Fig. 3 is a view taken on line 3—3 of Fig. 2.

Fig. 4 is a view taken on line 4—4 of Fig. 2.

Fig. 5 is a view taken on line 5—5 of Fig. 2.

Fig. 6 is a view in section through the hinge portion of the trousers hanger.

Fig. 7 is a view taken on line 7—7 of Fig. 6.

In the accompanying drawings I have used the numeral 1 to designate generally the body bar of the trousers hanger and the numeral 3 to designate generally the clamping bar which is coactive with the body bar to clamp the legs of trousers therebetween in a manner to be explained. These bars are hingedly related together at one end by hinge means 5 so that they may be swung together into operative clamping position as illustrated in full lines in Fig. 2 and swung apart into inoperative non clamping position as illustrated by dotted lines in Fig. 2.

The body bar may comprise a solid heel section 7 and a channel section 9 of arched form which extends forwardly from the heel section and ends in a clamping section 11 of generally enlarged rectangular configuration. Fixed to said clamping section 11 and extending forwardly therefrom are a pair of transversely spaced wires or rod-like members 13, which are connected at their forward ends by an inwardly curved keeper member 15. The wires 13 are sufficiently rigid to function in the desired manner, as will be explained, but do have a degree of spring or "give" to them.

The clamping bar 3 may comprise a solid heel section 17 which, as will become apparent as this description 30 proceeds, cooperates through the hinge means 5 with the heel section 7 of body bar 1. Extending forwardly from heel section 17 is a half round hollow section 19 which is a spring or "give" section and I provide a full round clamping section 21 on the forward end of section 19. 35 This clamping section 21 is coactive with clamping section 11 of the body bar 1. A further spring or "give" section 23 of half round hollow construction extends forwardly from clamping section 21 and at its outer end is bent inwardly as at 25 to form a further clamping section 40 coactive with a portion of wires 13. An inwardly extending catch 27 is formed on the end of clamping section 25, the catch having a downwardly and rearwardly extending cam surface 29 terminating in a shoulder 31.

Any suitable type of wire hook may extend through clamping section 11 to provide a hook 33 extending from one side of the hanger and, if desired, an eye 35 may extend from the other side of the hanger. It will be understood that the hook 33 functions to suspend the hanger from a clothes pole or the like in a clothes closet.

The hinge means 5 which hingedly connects the body and clamping bars at their heel ends comprises a pair of hinge plates designated in their entirety by the numeral 37, there being a hinge plate associated with each bar on each side thereof. While the hinge plates may be of any suitable and convenient configuration, I preferably form each of them with a generally triangular base 39 which is provided with an extension 41 from which a pair of reinforcing arms 43 project.

Each hinge plate is connected to each bar by means of 60 pivot screws or pins, one of such screws 45 extending through the base sections 39 of each hinge plate and through the heel portion 7 of body bar 1 and the other pivot screw 47 extending through the extensions 41 of each hinge plate and through the heel portion 17 of clamping bar 3.

I provide a widened groove or transversely extending recess 49 in the undersurface of heel 7 of body bar 1 and opening into and extending upwardly and forwardly from the recess 49 is a further hole or recess 51 which is provided in the heel 7.

Fixed to each hinge plate 37 and extending therebe-

tween is what I shall term a "control pin" 53 which extends through the groove 49 in heel 7. The control pin, for a reason to be hereinafter explained, is of less diameter than both the width and depth of groove 49 so that it may be capable of limited movement therein. I position a coil compression spring 55 in the recess 51, the spring being of a length to bear against the bottom of the hole or recess 51 and to extend a short distance outwardly of said hole and into engagement with control pin 53 biasing it rearwardly and into engagement with the rear wall 57 of transverse groove 49.

With the hinge means components assembled as described, and with the bars swung apart as illustrated in dotted lines in Fig. 2 so that the catch 27 of clamping bar 3 is not hooked over keeper member 15, the legs of a pair of trousers may be positioned or draped over either one of the bars whereupon clamping bar 3 may be swung on its pivot 47 until cam surface 29 of catch 27 comes into contact with keeper member 15, continued pressure of the two bars in a direction toward each other will cause the cam to ride up on the keeper member and to axially move the clamping bar forwardly causing the hinge plates to pivot on pin 45 and moving control pin 53 forwardly in its recess to compress the spring 55. When the bars have moved together a sufficient amount the shoulder 31 on the catch will ride over the keeper member and the spring 55 will force clamping bar 3 rearwardly so that the catch 27 will be firmly held and locked against or over keeper member to maintain the trousers in clamped position between the bars. It will be recognized that the walls of groove 49 limit the forward and rearward axial movement of clamping bar 3 relative to body bar 1.

With the pants properly positioned as described the center seam of each trousers leg which is the thickest part thereof will be clamped between clamping sections 11 and 21, while edge portions of the trousers legs will be clamped between section 25 and wires 13. Due to the thickness of the legs of the trousers it will be appreciated that it will be desirable that parts of the bars be endowed with a degree of spring or "give" to accommodate the thickness of the trousers legs clamped therebetween. The spring or "give" sections of the bars which have been described function in this manner.

With the body and clamping bars in operative clamping position as just described only a simple manipulation is necessary to release the catch from its position locked

by keeper member so that the bars may swing to inoperative non-clamping position so that the trousers may be removed. Such release of the clamping bar is effected by exerting a forward and downward pressure on the heel 17 of clamping bar 3, which pivots the hinge plates on pin 45, moves control pin 53 forwardly against the action of the spring and results in a forward axial movement of clamping bar to remove the catch from the keeper.

While I have illustrated in Fig. 2 of the drawings the body bar 1 in uppermost position it will be understood that the clamping and unclamping of the bars may be effected just as well with the positions of the bars reversed from that shown in the drawing.

I claim:

1. A trousers hanger including a pair of clamping bars adapted to clamp therebetween the legs of a pair of trousers, a hinge means including a plate pivotally connected to each bar on one side thereof adjacent the rear ends of the bars and a further hinge plate pivotally connected to each bar on the opposite side thereof adjacent the rear ends of the bars, said hinge means providing for swinging movement of the bars and limited relative axial movement thereof, one of said bars being provided with a transverse groove therein extending thereacross between said hinge plates, a control pin fixed to said hinge plates and extending therebetween and within said groove, said control pin being dimensionally reduced relative to the groove, and spring means mounted in said bar with the groove and in engagement with said control pin to constantly bias it rearwardly to urge one bar rearwardly relative to the other bar, and further means on the forward ends of said bars coercive to releasably lock the bars in operative clamping position when one of the bars is moved axially rearwardly relative to the other bar.

2. A trousers hanger in accordance with claim 1 wherein said bar with the groove is provided with a recess opening into said groove and extending diagonally forwardly therefrom, and said spring means is mounted in said recess.
